CLAIM

I claim the ornamental design for a hip and groin wrap for applying cooling and compression, as shown and described.

DESCRIPTION

FIG. 1 is a front perspective view of a hip and groin wrap for applying cooling and compression worn on the right leg, showing my new design;

FIG. 2 is a front perspective view thereof;

FIG. 3 is a rear perspective view thereof;

FIG. 4 is a right side perspective view thereof;

FIG. 5 is a left side view thereof;

FIG. 6 is a top plan view thereof;

FIG. 7 is a bottom plan view thereof;

FIG. 8 is a front perspective view thereof shown in use, with the broken lines being for illustrative purposes only and forming no part of the claimed design;

FIG. 9 is a right side view thereof;

FIG. 10 is a front perspective view of a second embodiment of a hip and groin wrap for applying cooling and compression worn on the left leg, showing my new design;

FIG. 11 is a left side perspective view of FIG. 10; and,

FIG. 12 is a rear view of FIG. 10.

The dotted lines applied to the wrap are understood to represent stitching.
